OUTBOARD MOTOR LOCK

Howard A. Foreman and Howard E. Foreman, Racine,
Wis., assignors to Racine Stamping Corporation, Racine,
Wis., a corporation of Wisconsin

Application April 7, 1953, Serial No. 24,394

Term of patent 14 years

(Cl. D50—7)

To all whom it may concern:

Be it known that we, Howard A. Foreman and Howard E. Foreman, citizens of the United States, residing at Racine, county of Racine, State of Wisconsin, have invented a new, original, and ornamental Design for Outboard Motor Lock, of which the following is a specification, reference being had to the accompanying drawing, forming a part hereof.

Fig. 1 is a perspective view of an outboard motor lock, showing our new design; and

Fig. 2 is an end view, showing same in locked condition.

We claim:

The ornamental design for an outboard motor lock, as shown.
